UNITED STATES PATENT OFFICE.

SAMUEL W. BARR, OF MANSFIELD, OHIO.

CASH-CARRIER.

SPECIFICATION forming part of Letters Patent No. 394,326, dated December 11, 1888.

Application filed June 13, 1888. Serial No. 276,962. (No model.)

To all whom it may concern:

Be it known that I, SAMUEL W. BARR, a resident of Mansfield, in the county of Richland and State of Ohio, have invented certain new and useful Improvements in Cash and Package Carriers; and I do hereby declare the following to be a full, clear, and exact description of the invention, such as will enable others skilled in the art to which it appertains to make and use the same.

My invention relates to an improvement in cash-carriers, the object being to furnish a simple and convenient device for the quick attachment of a carrier-receptacle to a traveling car at a station and its instant release to lower it to the hand of the operator by a downward pulling movement of a cord, which also serves to elevate the package-receptacle from the counter to the track ready for dispatching to another point on the track-line.

While the subject of the present invention is applicable to different apparatus for carrying cash and packages, I prefer to use it in connection with the two-wire apparatus peculiar to cash and package carriers of my invention, patents for which have already been allowed, and it will be shown and described in connection with such a preferred form of apparatus.

Referring to the drawings making a part of this specification, Figure 1 is a side elevation of the complete mechanism employed at one end of a line or at a sending and receiving station. Fig. 2 is a top plan view of the rear portion of the mechanism shown in Fig. 1. Fig. 3 is a top plan view of front portion of the device shown in Fig. 1. Fig. 4 is a transverse section in elevation taken on the line xx , Fig. 1, viewed from the front. Fig. 5 is a cross-section in elevation taken on the line xx , viewed from the rear side or looking to the front. Fig. 6 is a cross-section in elevation taken on the line zz , Fig. 1. Fig. 7 is a side view, in section, of the latch-bar for holding the goods-receptacle and connected parts. Fig. 8 is a detached perspective view of the latch-head that is formed on the end of the spring-actuated locking-slide rod. Figs. 9, 10, and 11 are views of detached parts.

A represents a depending hanger secured to an elevated fixed point in the room where the cash and package carrier is located, and

which supports the line-wires, as well as the receiving and dispatching mechanism at a station, and as this is duplicated at each end 55 of a track-line it will only be necessary to illustrate and describe one station outfit to render clear the operation of a complete line or an extensive system consisting of a number of transportation-lines, it being understood that in the system now under consideration each line is complete in itself and extends from a clerk's station to a cashier's stand and bundle-table that is generally adjacent thereto. The lower end of the hanger 60 is bent to form a bracket, which is bifurcated at the lower end, A', to receive between its parallel limbs the rocking bar B, pivoted at a thereto.

A depending cord, A², is secured to the 70 rearwardly-extended end a' of the bar B, having a handle, a³, attached to its lower end for accommodation of the operator in dispatching a car from the station, as will be further explained in its order.

Below the rocking bar B a parallel track-supporting limb, B', is hinged at b to the bar B, thus allowing it to swing downwardly. The front end of this limb and also the front end of the bar B are forked to receive clips 80 b², that are pivoted therein, and to which the upper and lower line-wires, 1 2, of the car-track are secured, said wires lying in the same vertical plane adjacent to each other.

A depending ear, b', is made integral with 85 the limb B', and is perforated to receive a slide-rod, B², on the forward end of which a bent clip-plate, b², is attached, the loop of this clip-plate being hooked over the limb B' to have sliding contact therewith.

Between the clip-plate b² and ear b' a spiral spring, B³, is placed upon the slide-rod B², it being of such length as to exert expansive force against the clip-plate to hold the rod 90 forwardly projected until the cross-pin b⁶ impinges against the ear b', as shown in Fig. 1.

The front end of the slide-rod B² is enlarged to form a sheave-head, B⁴, which is slotted at 11' l², leaving the parallel walls 3 4 5 6 integral with the front and rear portions of the head, and between which the grooved sheave-wheels M M are journaled. (See Fig. 2.)

As before explained, the line-wires 1 2 are extended between two hangers, A, located at

such points as afford the shortest direct route from one station to the other, and are stretched taut, so that a pull upon the cord a^2 will spread these line-wires apart at the end of the line where such a draft is made upon the handle of the pendent cord named.

On the wire 1 the car that is used to transport a package and cash receptacle from one station to the other is suspended. This car 10 consists of a frame, D, on which there are two pairs of grooved wheels, $D^3 D^4$, the wheels of each pair being in the same vertical plane, the upper wheels, D^3 , being preferably made of greater diameter than the lower wheel, D^4 . 15 These pairs are so relatively located that each have their grooved peripheral faces nearly in contact, a pair being placed at each end of the car-frame D.

On the end of the car-frame nearest the 20 hanger A (shown on the drawings) two parallel limbs, D^2 , are downwardly projected, preferably at right angles with the horizontal frame-piece D, considered lengthwise of said frame, said limbs D^2 being separated a suitable distance apart to accommodate other parts, which will be described farther on.

At the rear end of the frame D a bifurcated portion, D^5 , is bent or curved downwardly a short distance. This ends in a slotted enlargement, h , to which is pivoted the latch-bar H, which is curved, as shown in Figs. 1 and 7, the front end having a downwardly-bent hook end, f , formed on it, said hook end of the latch-bar extending beyond the depending parallel limbs D^2 of the frame-piece D, between which this end of the latch-bar is made to rest when it is in position to retain a basket or other package-receptacle.

Two ears, $k k^2$, formed on the lower side of 40 the latch-bar H, are perforated to receive and slidably support the locking-rod I, said rod having a curved body, which is rounded to be loosely embraced by the coiled elongated spiral spring m' , that bears with one end 45 against the ear k^2 , the other end being in contact with the adjustable collar k' , which latter is so adjusted that a proper compression of the spiral spring m' is effected. Between the collar k' and ear k another spiral spring, 50 m , is placed upon the locking-rod I, which exerts a spring expansive force in a direction toward the hook end of the latch-bar H. The depending limbs D^2 of the car-frame D have their adjacent inner surfaces near their free 55 lower ends cut away, as shown in Fig. 9, to form a retaining-recess for the latch-head G, which is formed on or attached to the end of the rod I nearest to these limbs.

The latch-head G is shown in perspective in 60 Fig. 8, and consists of a block that is either perforated to be riveted on the shouldered end of the rod I or is made integral with it, and has laterally-projecting rounded lugs u , formed on the sides in line with each other. 65 These lugs are of such a length as to allow them to engage the inclines e^5 , cut on the lower ends of the mating limbs D^2 , and by upward

pressure cause the spring m' to contract enough to allow said lugs u to enter the mating recesses cut in the adjacent walls of the 70 limbs D^2 . As shown in Figs. 7 and 8, a projecting tongue, s , made on the latch-head G, engages loosely the longitudinal groove u' , formed in the lower surface of the front end of the latch-bar H. When the lugs u enter 75 these recesses e^4 , the compressed spring m' , by its release and expansion, forces the lugs against the depending flanged walls e , and if there is weight placed on the latch-bar near its center the lugs will be carried into the corners e^6 of the recesses, where they will rest and hold the latch-bar securely interlocked with the limbs D^2 .

Should it be desired to release the latch-bar H, its hooked end f should be elevated sufficiently to carry the lugs u up past the walls e on the sides of the same opposite to where they entered at e^4 , which movement will fully release the spiral springs $m m'$ from compression and force, by their expansion, the 90 latch-head G outside of the limbs D^2 toward the hooked end f of the latch-bar H, and in case a weight is suspended on this latch-bar its gravity will draw the hooked end of the bar down and force the same from contact 95 with the limbs D^2 .

The basket or package-receptacle (not shown) is provided with suspension-rods w , which are secured to the frame w' , in which the grooved pulley w^2 is pivoted to revolve, 100 said pulley being intended to engage the curved surface of the latch-bar H, and thus support the basket pendent below the car-frame; and in order to prevent the loaded package-receptacle from improper surging 105 action longitudinally of the bar H a locking device is provided, which I will now describe.

On the upper surface of latch-bar H a curved upwardly-projecting finger, 7, is formed at such a point with regard to the length of 110 the bar and frame D that it will produce an abutment to restrain the wheel or roller w^2 from rolling past the center of length of the latch-bar when it is located on it.

Between the limbs D^2 a cross-bar, 8, is introduced, which is immediately above the pivoted end of the arm 9, that projects toward the finger 7, having its free end forked to press at two points on the side of the wheel w^2 opposite to the finger just named, this 120 forked end being adapted to engage the side of the grooved wheel w^2 .

Between the bifurcated portion of the frame D a horizontally-projected latching-finger, 10, is pivotally secured, which is notched at 11 125 to engage the top bar, 12, of frame w' when the basket to which this frame is attached is in position. Thus it will be seen in Fig. 1 that the wheel w^2 is held from displacement at three points when it rests near the center 130 of the latch-bar H. The latching-finger 10 is suspended by a link, 13, which is free to move vertically, but holds the finger from falling below a horizontal plane.

To provide for the elevation of the package and cash receptacle from the counter to the suspended car above the same, a pair of coiled-wire springs, 14, are attached to the top 5 face of the sheave-head B⁴, on each side near the rear end of the same, the set-screws *i* being made to bear with their heads on the cross-bar which joins the two springs integrally. Each spring consists of a single spiral coil, the free ends of which extend forwardly and terminate in the eyes 16, the horizontal portions 15 of the spring-body being engaged by the depending loops J, these latter having their upper ends secured in the 10 ears *v*, that project from the side of the sheave-head B⁴, so as to hold them firmly and enable them to afford lateral support to the free ends of the portions 15 and permit them to vibrate vertically.

20 There is a loop-spring, C, secured on the projection l⁵, formed on the forward end of the bar B, the parallel limbs C' of which spring are separated sufficiently to straddle the vertical arms D' of the car-frame and hook onto 25 the front edges at C². (See Fig. 1.)

The provision of the spring latching device just named is for the retention of a car at a station in close contact with the end of the projecting forked ends *p* of the slide-rod B² 30 until it is ready for dispatch to the other end of the line, and it is evident that shock of an abutment of the incoming car at either end of the track-line will be taken up by the yielding action of the spiral spring B³, which is 35 provided for such a purpose.

To elevate a basket or other package-receptacle from the counter to the car and lock it in place pendent below said car, the cord O is provided, which is doubled, the separate 40 ends being passed upwardly through the eyes 16 of the spring-limbs 15, thence through the slots l² of the sheave-head B⁴, engaging the top surfaces of the grooved sheave-wheels M, and thence downwardly through the slots l² on 45 the other side of these pulleys, the depending portions of the cord being of sufficient length to reach the counter, where they may be secured at any convenient point.

Where the bend or doubling of the cord O is made below the eyes 16, a metal U-shaped short piece of pipe, L, is strung upon the cord to receive the wear incident to the engagement of the cord-loop with the hook *f* of the 50 latch-bar H, said pipe-jacket being placed in the hook after the basket-hanger frame w' has been located on the latch-bar H.

In operation the weight of the basket, together with the suspension device that loosely supports it on the latch-bar H, will be sufficient to cause it to quickly descend on the bight of the cord O if the latter is slackened to permit such a descent of the basket. If a basket is elevated, the latching device previously described will secure the end of the 60 latch-bar between the depending limbs D' of the car-frame D, and when the car, with a basket or package-receptacle, reaches a clerk's

station it may remain in secured position there by reason of the hooked engagement of the limbs C' of the spring-latch with the 70 frame D, and to lower it a pull on the cord O will release the latch-head G, so that the latch-bar H will swing down sufficiently to allow the wheel w' on the frame w' to leave the bar and descend gently in the lowering 75 bight of the cord O in an obvious manner. When a basket or other style of package-receptacle is elevated, if this is performed rapidly, so as to cause the ends of the pipe-jacket L to impinge on the eyes 16, the spring portions 80 15 will prevent any objectionable shock of the engaged parts.

When a car is to be dispatched from either end of the line, it is only necessary to depress the rear end of the pivoted bar B by pulling 85 the cord a² or handle a³, which movement will elevate the other end of the bar B, carrying the spring C above the car-frame D, to release its hooked engagement with it. The elevation of the forward end of the bar B will also spread 90 the wires 1 2 of the track, so that a propelling impetus will be imparted to the frame of the car by the divergance of the track-wires. This means of propulsion of the cars is shown in other cash-carrier devices of my invention 95 and is not specially claimed in this case.

From the foregoing it is evident that in the form of cash-carrier herein presented the car may be arrested without shock, held in place till released, and its receptacle lowered or elevated by pulling in a downward direction on the same cord, thus affording a simple, reliable, and very convenient device for the designed purpose.

Many slight changes might be made in the 105 constructive details of this apparatus without departure from the spirit of my invention or exceeding its scope; hence I do not wish to be restricted to the exact forms herein shown; but,

Having fully described my invention, what I claim as new, and desire to secure by Letters Patent, is—

1. In a cash and package carrier, the combination, with a car-frame, of a hinged latch-bar and a movable head having projections thereon which engage one end of the car-frame for locking the free end of the latch-bar to said frame. 115

2. In a cash and package carrier, the combination, with a car-frame having depending limbs, of a curved latch-bar forming a track for the wheel of a cash or package receptacle and provided with a stop or abutment, the said latch-bar being hinged at one end to one 120 depending limb of the car-frame and detachably secured at its other end to another depending limb of said frame, substantially as set forth.

3. In a cash and package carrier, the combination, with a car-frame, of a curved latch-bar hinged at one end to the frame and provided with an abutment against which the wheel of the cash or package receptacle rests, 130

- and a movable head having projections thereon which engage one end of the car-frame for locking the free end of the latch-bar to said frame, substantially as set forth.
5. In a cash and package carrier, the combination, with a car-frame, of a hinged latch-bar and a spring-actuated movable head mounted on said latch-bar and provided with projections which engage the car-frame for locking the free end of the latch-bar to said frame.
10. In a cash and package carrier, the combination, with a car, a hinged latch-bar, and a spring-actuated movable head mounted on said latch-bar and having projections thereon which engage one end of the car-frame for locking the free end of the latch-bar to said frame, of a rope to release, lower, and elevate the swinging end of the latch-bar, substantially as set forth.
15. In a cash and package carrier, the combination, with a frame having a series of wheels arranged in pairs, of a latch-bar adapted to receive a grooved wheel carrying the package-receptacle, a movable head having projections thereon which engage one end of the frame for locking the free end of the latch-bar to said frame, and a rope adapted to elevate, release, and lower the latch-bar, substantially as set forth.
20. In a cash and package carrier, the combination, with a car-frame, two pairs of wheels supported above the horizontal portion of the frame in the same plane, a hinged latch-bar having a curved upwardly-projecting finger and adapted to be locked fast to and to be released from the car-frame, and a grooved wheel pivoted on a package-receptacle frame, of a pivoted latching-finger that hooks fast to the top of the package-receptacle frame and a forked pivoted arm that coacts with the pivoted latching-finger to lock the grooved wheel against the curved upwardly-turned finger of the latch-bar, substantially as set forth.
25. In a cash and package carrier, the combination, with a car-frame and a latch-bar hinged at one end to said frame, of a sliding rod carrying a locking-head adapted to engage the frame for holding the free end of the latch-bar in elevated position and springs mounted on said rod for moving the latter lengthwise, substantially as set forth.
30. The combination, with a car and a hinged latch-bar, of a rope for engaging the free end of the latch-bar and a spring for normally holding the rope out of contact with the free end of the latch-bar.
35. The combination, with a car and a hinged latch-bar having a hook at its free end, of a rope for engaging the hook on the end of the latch-bar and a spring for normally holding the rope out of contact with the hook.
40. The combination, with a car-frame having projections, a hinged latch-bar, and a sliding head having projections adapted to be engaged by the projections on the car-frame, of a rope for engaging the free end of the latch-bar and a spring for normally holding the rope out of contact with said latch-bar.
45. A cash and package carrier apparatus comprising the following elements: a pivoted bar, a hinged limb carrying a spring-actuated buffer, a pulley mounted on the buffer, a rope or cord passing over the pulley, a car-frame having a hinged latch-bar adapted to be engaged by the rope or cord, and a handle for moving the pivoted bar.
50. A cash and package carrying apparatus comprising the following elements: a pivoted bar, a hinged limb carrying a buffer, a pulley mounted on the buffer, a rope or cord passing over the pulley, a car-frame having a hinged latch-bar adapted to be engaged by the rope or cord, and a sliding head for locking the free end of the hinged latch-bar to the car-frame, substantially as set forth.
55. A cash and package carrying apparatus comprising the following elements: a pivoted bar, a limb hinged to said bar and carrying a buffer, two track-wires, a cord or rope supported on a bearing carried by the buffer-rod, a car-frame, and a hinged latch-bar, the latter adapted to be engaged by the rope or cord.
60. The combination, with a car-frame and a hinged latch-bar having a stop or abutment thereon, of an arm and a latching-finger pivoted to the car-frame in positions to engage the wheel of the cash or package receptacle.
65. A cash and package carrying apparatus comprising the following elements: a pivoted bar carrying a car-holding device, a limb hinged to said bar and carrying a buffer, a rope or cord supported on a bearing carried by the buffer-rod, and a car-frame having a hinged latch-bar adapted to be engaged by the rope or cord.
70. The combination, with a frame having a latch-bar hinged at one end thereto and a movable head having projections adapted to engage the frame for locking the free end of the latch-bar to the frame, of a pivoted latching-finger located above the latch-bar, substantially as set forth.
75. A cash and package carrying apparatus comprising the following elements: a pivoted bar, a hinged limb carrying a buffer, a pulley mounted on the buffer, a rope or cord passing over the pulley, a car-frame having a hinged latch-bar adapted to be engaged by the rope or cord, and a handle for moving the pivoted bar.
80. A cash and package carrying apparatus comprising the following elements: a pivoted bar, a hinged limb carrying a buffer, a pulley mounted on the buffer, a rope or cord passing over the pulley, a car-frame having a hinged latch-bar adapted to be engaged by the rope or cord, and a sliding head for locking the free end of the hinged latch-bar to the car-frame, substantially as set forth.
85. A cash and package carrying apparatus comprising the following elements: a pivoted bar, a limb hinged to said bar and carrying a buffer, two track-wires, a cord or rope supported on a bearing carried by the buffer-rod, a car-frame, and a hinged latch-bar, the latter adapted to be engaged by the rope or cord.
90. The combination, with a car-frame and a hinged latch-bar having a stop or abutment thereon, of an arm and a latching-finger pivoted to the car-frame in positions to engage the wheel of the cash or package receptacle.
95. A cash and package carrying apparatus comprising the following elements: a pivoted bar carrying a car-holding device, a limb hinged to said bar and carrying a buffer, a rope or cord supported on a bearing carried by the buffer-rod, and a car-frame having a hinged latch-bar adapted to be engaged by the rope or cord.
100. The combination, with a frame having a latch-bar hinged at one end thereto and a movable head having projections adapted to engage the frame for locking the free end of the latch-bar to the frame, of a pivoted latching-finger located above the latch-bar, substantially as set forth.
105. The combination, with a frame having a latch-bar hinged at one end thereto and a movable head having projections adapted to engage the frame for locking the free end of the latch-bar to the frame, of a pivoted latching-finger located above the latch-bar, substantially as set forth.
110. The combination, with a frame having a latch-bar hinged at one end thereto and a movable head having projections adapted to engage the frame for locking the free end of the latch-bar to the frame, of a pivoted latching-finger located above the latch-bar, substantially as set forth.
115. In testimony whereof I have signed this specification in the presence of two subscribing witnesses.

SAMUEL W. BARR.
